DISPLAY RACK

Shulman A. Moog, St. Louis, Mo., assignor to
 St. Louis Spring Company, St. Louis, Mo., a
 corporation of Missouri

Application May 9, 1932. Serial No. 610,139

3 Claims. (Cl. 211—60)

This invention relates generally to display racks and has more particular reference to a rack especially adapted for the display of bar material, such as, for instance, automotive spring-leaves 5 and the like.

My invention has for its prime object the provision of a sturdy, durable, and readily manufactured skeleton or open rack for the efficient storage and display in tiers or superposed rows of 10 spring-leaves and other bar articles, the rack including article-intervening members easily adjustably spaced the one from the other for maintaining the articles in the several tiers or rows in 15 orderly stacks or columns for convenient individual accessibility.

And with the above and other objects in view, my invention resides in the novel features of 20 form, construction, arrangement, and combination of parts hereinafter described and pointed out 25 in the claims.

In the accompanying drawing,—

Figure 1 is a perspective view of a spring-leave 30 display-rack embodying my invention;

Figure 2 is a condensed side view of the display-rack, the middle portion thereof being broken away, illustrating the adjustable or varied spacing of the vertical leak-intervening bars for 35 reception and stacking of bar-articles of different widths; and

Figure 3 is a fragmentary sectional view 40 through one of the rack side-frames, taken approximately along the line 3—3, Figure 2.

Referring now more in detail and by reference 45 characters to the drawing, which illustrates a preferred embodiment of my invention, the display rack includes a pair of suitably spaced skeleton or open frames A, each comprising a pair of also suitably spaced corner posts or standards 1 50 suitably connected or tied-together in parallel relation by a top cross-member 2 and a series of lower cross or tier-members 3 disposed in suitably spaced relation one from the other and from the top-member 2.

The posts 1 of each frame A are also connected 55 to the corresponding posts 1 of the other frame A by respective top and bottom tie-bars 4, the respective posts 1 being suitably provided with preferably integral floor-engaging members or feet 5, as best seen in Figure 1, for support upon or attachment to a floor or the like.

The respective cross-members 2, 3, of each frame A are disposed in also horizontal registration with the corresponding cross-members 2, 3, of the other frame A, the series of superposed members 2, 3, in the respective frames A being pro-

vided each with a series or plurality of spaced apertures 6 respectively disposed in vertical registration with the corresponding apertures in the other members 2, 3, of the frame, as best seen in Figure 2.

Each horizontally registering pair of tier-members 3 is adapted for supporting a plurality of the bar-articles B, the articles B spanning between the pair of supporting members 3, as indicated in dot-dash lines in Figure 1.

For segregating or separating the displayed articles B on the tier-members 3, a requisite number of vertical rods 7 are inserted preferably downwardly each through a particular series of the vertically registering apertures 6 for intersecting the series of superposed cross-members 2, 3, of the respective frames A, each pair of adjacent rods 7 providing between the respective pairs of superposed tier-members 3 an article-receptive approximately rectangular frame-opening 8, in and through which the articles B may be endwise inserted for residing on the lower tier-member of the pair, the frame-openings 8 in one frame A being horizontally aligned with the frame-openings 8 in the other frame A, as will be understood from Figure 1.

Each rod 7 is provided at its upper end with a head 9 for engaging the upper face of the top cross-member 2 for suspending the particular rod 7 removably therefrom, and a suitable retainer-plate 10 is mounted over the series of rod-heads 9 residing on the member 2 for preventing dislodgement of the rods 7 from the frame A, the retainer-plate 10 being preferably detachably engaged with the frame-member 2 by means of suitable bolts or other suitable fastening elements 11, as best seen in Figure 2.

As illustrated in Figure 1, all the rod-receptive apertures 6 in the frames A may be occupied by article-separating rods 7 provided, of course, that the respective bar-articles B are not of greater width than the spacing between the rods 7. However, as illustrated in Figure 2, a lesser number of rods 7 may be employed and adjustably disposed in and through the apertures 6 for mounting the rods 7 at different spacings in the frame A suitable for reception of bar-articles B of various widths in the so-provided frame-openings 8.

The bar-articles B may, most conveniently for increasing the storage capacity of the rack, be stacked or piled one upon another in the frame-openings 8, the rods 7 then most effectively providing a lateral support for the stack of articles B, as illustrated in Figure 2.

I might add that preferably the frame members 110

2, 3, are provided with flanged ends and detachably assembled on and with the posts 1 by means of bolts or other suitable fastening elements 12, and the tie-bars 4 are likewise connected to the respective frames A by similar bolts 12'. Hence 5 the rack may be readily collapsed or disassembled to so-called "knocked-down" condition for shipping purposes and the like.

The several members of the rack are constructed of metal or other preferably unbreakable material, and I thus provide a most convenient, economical, sturdy, durable, and highly useful rack for displaying relatively awkward and bulky bar-articles, as automotive leaf-springs 10 and the like. The displayed articles are readily 15 visible from all sides thereof and may with ease, facility, and convenience be removed from or replaced in the rack one by one without interfering with or disturbing the other articles in the rack.

20 It will be understood that changes and modifications in the form, construction, arrangement, and combination of the several parts of the rack may be made and substituted for those herein shown and described without departing from the 25 nature and principle of my invention.

Having thus described my invention, what I claim and desire to secure by Letters-Patent is,—

1. In a display rack, a pair of upstanding skeleton frames each including spaced and opposed 30 parallel corner post-providing strips, an upper cross strip and a series of vertically spaced lower cross strips each provided at its opposite ends with lateral flanges and at said flanges abutted 35 flatwise against the inner face of and rigidly fixed to the corner-strips, each of said cross strips having a series of spaced openings and the openings of the several cross strips being in aligning registration, a series of upright rods depending from the upper cross strip through aligning openings 40 of and thereby intersecting the lower cross strips, and tie-plates fixed flatwise at their opposite ends to and upon the outer face of the corner-strips for tying said frames rigidly together in spaced parallel relation with the cross strips and upright rods thereof in registration for forming 45 superposed rows of vertically aligning bar-article accommodating seats and apertures.

2. In a display rack, a pair of upstanding skeleton frames each including spaced and opposed parallel corner post-providing strips, an upper cross strip, and a series of vertically spaced lower cross strips each provided at its opposite ends with lateral flanges and at said flanges abutted flatwise against the inner face of and rigidly fixed to the corner-strips, each of said cross strips having a series of spaced openings and the openings of the several cross strips being in aligning registration, a series of upright rods removably depending from the upper cross strip through selected series of aligning openings of and thereby intersecting the lower cross strips, and tie-plates fixed at their opposite ends to and upon the outer face of the corner-strips for tying said frames rigidly together in spaced parallel relation with the cross strips and upright rods thereof in registration for forming superposed rows of vertically aligning bar-article accommodating seats and apertures of selected width. 80

3. In a display rack, a pair of upstanding skeleton frames each including spaced and opposed parallel corner post-providing strips, an upper cross strip and a series of vertically spaced lower cross strips each provided at its opposite ends with lateral flanges and at said flanges abutted flatwise against the inner face of and rigidly fixed to said corner-strips, each of said cross strips having a series of spaced openings and the openings of the several cross strips being in aligning registration, a series of headed rods removably engaging the upper cross strip and removably depending therefrom through selected series of registering openings of and thereby intersecting the lower cross strips, tie-plates fixed flatwise at their opposite ends to and upon the outer face of the corner-strips for tying said frames rigidly together in spaced parallel relation with the cross strips and upright rods thereof in registration for forming superposed rows of vertically aligning bar-article accommodating seats and apertures of selected width, and a cross plate disposed flatwise longitudinally over and bolted detachably to the upper cross strip over the heads of said rods 100 for removably securing the rods operatively in position. 105
